UNITED STATES PATENT OFFICE.

THOMAS BEACH, OF FREEPORT, PENNSYLVANIA.

DESIGN FOR A VEHICLE-TIRE.

SPECIFICATION forming part of Design No. 33,647, dated December 4, 1900.

Application filed November 7, 1900. Serial No. 35,771. Term of patent 14 years.

To all whom it may concern:

Be it known that I, THOMAS BEACH, a citizen of the United States of America, residing at Freeport, in the county of Armstrong and 5 State of Pennsylvania, have invented a certain new and useful Design for a Vehicle-Tire, of which the following is a specification, reference being had therein to the accompanying drawings.

This invention relates to a certain new and original design for a tire; and it consists in the novel form and configuration of the design to be hereinafter more particularly described and specifically claimed.

15 In describing the invention in detail reference is had to the accompanying drawings, forming a part of this specification, and wherein like numerals of reference indicate corresponding parts throughout the views, in 20 which—

Figure 1 is a perspective view of my new and novel design, and Fig. 2 is a vertical sectional view thereof.

In the drawings the reference-numeral 1

indicates a concentric tire, having formed on 25 its face cut-away portions 2, these cut-away portions forming a shoulder 3 and gradually incline or taper upwardly, forming an offset 4. The cut-away portions 2 are semicircular in form, as shown in Fig. 2. On the face of the 30 tire is formed projections 4, which are curved, as shown at 5, to the semicircular portions 6.

It will be noted that the here-described design produces a new and novel feature, which is clearly distinctive from other inventions of 35 this class, and the invention has a pleasing effect to the eye.

Having fully described my invention, what I claim as new, and desire to secure by Letters Patent, is—

The design for a tire, substantially as herein shown and described.

In testimony whereof I affix my signature in the presence of two witnesses.

THOMAS BEACH.
